UNITED STATES PATENT OFFICE

2,644,422

FROST INDICATOR FOR REFRIGERATORS

Richard J. Carberry, Erie, Pa., assignor to General Electric Company, a corporation of New York

Application December 21, 1950, Serial No. 201,972

20 Claims. (Cl. 116—114)

1

My invention relates to refrigerators and more particularly to frost indicators for refrigerator evaporators.

In many household refrigerators the food storage compartment is cooled by an evaporator whose surface is exposed to the air in the compartment. Consequently moisture condenses from the air on the substantially cooler surface of the evaporator and collects thereon as frost. In order to maintain a satisfactory efficiency of the refrigerating apparatus it is necessary to remove this frost from time to time, and hence it is desirable to call the user's attention to the thickness of frost collected thereon and particularly to call to his attention the presence on the evaporator of frost of a predetermined maximum thickness. In connection with horizontal, or full width, evaporators which extend substantially the full width of the food storage compartment and are covered by the evaporator door, it is difficult for the user to determine the amount of frost collected on the evaporator and hence easy for him to overlook the necessity for defrosting. Moreover, with this type of evaporator the thickest blanket of frost usually collects on the rear wall of the evaporator where it is completely concealed from the user's view. By my invention I have provided arrangements which clearly indicate to the user the thickness of frost collected on the evaporator and more particularly indicate the thickness of frost on the otherwise concealed rear wall of the evaporator. Moreover, the indicators are positioned so as to minimize the danger that the need for defrosting may be overlooked by the user.

It is an object of my invention to provide an improved arrangement for indicating the thickness of frost on a refrigerator evaporator.

It is another object of my invention to provide an improved arrangement for indicating the thickness of frost on a refrigerator evaporator each time the evaporator door is opened.

It is another object of my invention to provide an improved frost indicating arrangement particularly adapted for full width evaporators and including an element engaging the frost each time the evaporator door is opened to indicate the thickness of frost.

Further objects and advantages of my invention will become apparent as the following description proceeds and the features of novelty which characterize my invention will be pointed out with particularity in the claims annexed to and forming part of this specification.

In carrying out the objects of my invention I

2

provide a slidable member positioned between the side wall of the evaporator and the side wall of the liner forming the food storage compartment. This member includes a laterally extending element adapted to engage the frost on the rear wall of the evaporator, and the member is biased forwardly by a spring so as to bring this element into engagement with the frost. The slidable member is engaged by the evaporator door in its closed position to move the element away from the frost against the bias of the spring. The slidable member engages a pivoted or rotatable indicating element positioned at the forward portion of the food storage compartment, and the slidable member is connected to the indicating element so that the amount of movement of the slidable member, as determined by the thickness of frost under rear wall of the evaporator, determines the position of the indicating element. Suitable indicia are employed for indicating the thickness of frost or at least for indicating when an abnormal amount of frost has collected on the evaporator.

For a better understanding of my invention reference may be had to the accompanying drawings in which Fig. 1 is a view of a portion of a refrigerator cabinet illustrating an embodiment of my invention; Fig. 2 is a side elevation view showing details of one form of my invention; Fig. 3 is a plan view of the form of invention shown in Fig. 2; Fig. 4 is an enlarged view of a portion of the mechanism illustrating details of operation; Fig. 5 is a front view, partly broken away, of the indicating mechanism; Fig. 6 is a side elevation view of a modified form of my invention; Fig. 7 is a plan view of the form of invention shown in Fig. 6; Fig. 8 is a front sectional elevation view of a portion of the indicating mechanism; Fig. 9 is an elevation view of a portion of the front of the refrigerator illustrating the indicating arrangement; and Fig. 10 is a side elevation view of another modified form of my invention.

Referring to the form of invention illustrated in Figs. 1 through 5, there is shown a refrigerator 1 including an inner liner 2 defining a food storage compartment 3. The food storage compartment is cooled by an evaporator 4 which is of the horizontal, or full width, type extending substantially the full width of the food storage compartment 3. The access opening of the evaporator 4 is closed by a door 5 having a handle 6 thereon. The door 5 is hinged for movement about a horizontal axis, and is biased to its closed position by a conventional spring hinge 7. Spring

hinges are old and detailed showing and description thereof are not believed necessary.

During normal operation, the evaporator 4 being exposed to the air in the food storage compartment 3, moisture from the air condenses on the walls of the evaporator and collects thereon in the form of frost. This frost may eventually reach a thickness sufficient to reduce materially the effectiveness of the evaporator. The frost built up is particularly large along the rear wall 8 of the evaporator. In order to indicate to the user the thickness of frost collected on the evaporator and particularly the relatively large thickness of frost which may collect on the concealed rear wall 8, an indicating arrangement including a slidable member 9 is provided. The slidable member 9 is disposed in the space between the side wall 10 of the evaporator and the side wall 11 of the liner 2. The slidable member 9 includes a laterally extending portion or frost-engaging element 12 adapted to engage the frost on the rear wall 8 of the evaporator. The frost-engaging element includes a flat plate 12a so as to provide a large area of contact with the frost, thereby minimizing penetration of the frost by the frost engaging element.

For slidably mounting the slidable member 9 on the side wall 11 of the liner two supports or support members 13 and 14 are provided. The front support or bracket 13 is adjustably mounted on the side wall 11 at the front portion thereof by screws 15 and nuts 15a or other suitable fastening devices passing through elongated slots 16 in the bracket. The rear support or stud 14 is mounted at the rear portion of the side wall 11 by a screw 17 and nut 18 or other suitable fastening devices. The bracket 13 includes a return bent section 19 having an opening therein for slidably receiving the forward end of this slidable member 9. A strip 19a of suitable plastic material is mounted on the section 19 to provide a bearing surface for the slidable member 9. The rear portion of the slidable member 9 includes an elongated slot 20 within which the stud 14 is received for slidably supporting the rear end of the slidable member 9. The slidable member 9 is biased forwardly in a direction in which the frost-engaging laterally extending element 12 moves toward the frost on the rear wall 8 of the evaporator by a spring 21. One end of the spring engages the bracket 13 and the other end engages the slidable member 9.

To cover the space between the side wall 10 of the evaporator and the side wall 11 of the liner a filler strip 22 of plastic or other suitable material is employed. This filler strip is mounted on the flanged front surface 23 of the evaporator by screws (not shown) or other suitable fastening devices, and a gasket 24 for the evaporator door 5 overlaps the inner edge of the filler strip 22. The filler strip has an opening 25 provided therein through which the front end of the slidable member 9 projects. The evaporator door 5, when in its closed position against the gasket 24, moves the slidable member 9 rearwardly to the position shown in Figs. 2 and 3 and the solid lines in Fig. 4 wherein the frost-engaging element 12 is spaced from the frost 26 shown on the rear wall 8 of the evaporator. The evaporator door 5 is biased to its closed position by a spring or other suitable biasing device sufficiently strong to overcome the relatively weak biasing force of the spring 21.

It can be seen that each time the evaporator door 5 is opened the slidable member 9 is moved

by the biasing spring 21 from the rearward position illustrated in Figs. 2 and 3 and the solid lines in Fig. 4 to a forward position in which the frost-engaging element 12 engages the frost 26 on the rear wall 8 of the evaporator. The amount of this forward movement obviously varies dependent upon the thickness of the frost 26 on the rear wall of the evaporator, and is illustrated for one frost condition by the dotted lines in Fig. 4. This variation in the forward movement of the slidable member 9 depending on the frost thickness on the evaporator is utilized to move an indicating element visible from the front of the refrigerator to indicate the thickness of frost and ultimately the need for defrosting. In the form of invention illustrated in Figs. 1 through 5 the slidable member 9 is formed of generally channel cross section and includes a front face 27 projecting beyond the filler strip 22 and directly visible to the user when the evaporator door is in its open position. An opening 28 is provided in the upper portion of this front face 27 to provide a view of a portion 29 of an indicating element 30. The portion 29 constitutes a generally flat element somewhat wider than the opening 28. The indicating element 30 is pivotally mounted on the slidable member 9 by pin 31, so that the position of the portion 29 of this indicating element varies as the indicating element pivots about the pin 31. In order to effect such pivoting of the indicating element 30 coincident with the sliding movement of the slidable member 9 the bracket or support 13 is formed to provide an elongated opening or slot 32 which is inclined with respect to the line of movement of the slidable member 9. The pivot indicating element 30 is provided at its rear end with a laterally extending pin 33 which projects into the inclined slot 32.

It can be seen that movement of the pin 33 along the inclined slot 32 will effect a pivoting of the indicating element 30, the amount of this pivoting being dependent upon the extent of the movement of the pin 33 relative to the slot 32. This relative movement is utilized to indicate the frost thickness on the evaporator. Thus when the evaporator 5 is in its closed position and the slidable element 9 has therefore been moved rearwardly to the solid line position shown in Fig. 4 the pin 33 occupies the position substantially at the right hand end of the inclined slot 32 and the pivoted indicating element 30 is held in a position wherein the portion 29 is immediately behind the opening 28 in the front face 27 of the slidable member 29. When the evaporator door is opened by the user for access to the contents of the evaporator the biasing force exerted by the door on the slidable member 9 is removed and the slidable member 9 is moved forwardly by the biasing spring 21 until this forward motion is stopped by engagement of the frost-engaging element 12 with the frost 26 on the rear wall 8 of the evaporator. As the slidable member 9 moves forwardly the pin 33 moves with the slidable member 9 and rides upwardly in the inclined slot 32 effecting a counterclockwise pivoting of the indicating element 30. This pivoting effects a downward movement of the portion 29 of the indicating element, the amount of downward movement being dependent on the forward movement of the slidable member 9 and hence upon the thickness of the frost 26.

The condition when there is no frost present on the rear wall 8 of the evaporator is shown by the dotted lines in Fig. 4. In this situation

the frost-engaging element 12 has moved forwardly into direct engagement with the rear wall 8 of the evaporator and the motion of the slideable member 9 is sufficient to effect movement of the pin 33 to the dotted line position indicated, moving the indicating element 30 in a counter-clockwise direction to an extent sufficient to move the portion 29 of the indicating element completely below the opening 28 so that none of the portion 29 of the indicating element is visible through this opening 28. As varying thicknesses of frost build up on the rear wall of the evaporator the amount of forward movement of this slideable member 9 is limited to a varying extent and the position of the indicating element 30 and of its front portion 29 with the evaporator door in its open position varies. As the frost thickness increases progressively larger amounts of the portion 29 will be visible through the opening 28, indicating increasingly greater thickness of frost on the evaporator. Although in the arrangement described above the indicating element 30 is pivoted on the slideable member 9 and the inclined slot 32 is provided in the support or bracket 13, it will be apparent that, if desired, the parts could be reversed so that the indicating element is pivoted on the bracket 13 and the inclined slot 32 is provided in the slideable member 9.

The front face 27 of the slideable member 9 may be marked with suitable indicia to indicate directly, by relation of the indicia to the top edge of the portion 29, the thickness of frost on the evaporator. Alternatively such indicia may be omitted, reliance being had merely upon the progressively greater amount of the portion 29 visible to the opening to indicate to the user the increasing amount of frost and ultimately the need for defrosting. For greater noticeability the front face of the portion 29 may be painted in some conspicuous color, such as red, which will assist in calling the frost condition to the user's attention. For further accenting the noticeability a U-shaped member 34 may be secured to the interior of the slideable member 9 with a face 35 thereof spaced slightly rearwardly from the front face 27 of the slideable member 9. This face 35 may then be painted in some contrasting color, such as green. Hence when there is substantially no frost on the evaporator a green background will appear through the opening 28 and, as the frost thickness builds up and the red portion 29 gradually becomes visible through the opening 28, the green background will be progressively reduced and the red background progressively increased.

In Figs. 6 through 9 inclusive there is shown a modified form of my invention which operates on the same general principle as that previously described but differs in details of construction and in the use of a different form of indicating element. The same numerals have been used to designate corresponding parts in Figs. 1 through 5 and Figs. 6 through 9. As in a form previously described the evaporator 4 is disposed in the top portion of the food storage compartment 3 defined by the liner 2 and this evaporator extends substantially the full width of the food storage compartment. In the space between the side wall 10 of the evaporator and side wall 11 of the liner a slideable member 36 is disposed. Two supports or support members 37 and 38 are mounted on the liner at the front and rear portions respectively of the side wall 11. The front support 37 is mounted on the liner by a screw 39 and nut 40

or other suitable fastening device. The rear support 38 is secured to the liner by screws 41 or other suitable fastening devices. The rear support 38 is formed of plastic or other similar material and includes two horizontal passages, one of which is shown at 42, for slidably supporting the rods 43 and 44 of the slideable member 36. The slideable member 36 includes a laterally extending portion or element 45 adapted to engage the frost 26 collected on the rear wall 8 of the evaporator. The element 45 includes a covering piece of rubber tubing 45a to provide a relatively wide frost engaging surface, minimizing penetration of the frost by the element 45 and also minimizing adhesion to the frost. The front end of the slideable member 36 extends through an opening 46 in a filler strip 47 of plastic or other similar material which closes the space between the side walls 10 and 11 of the evaporator and liner respectively. The end of the slideable member 36 is bent at right angles in front of the filler strip 47 to present a relatively flat surface 48 which is engaged by the door 5 in its closed position for moving the slideable member 36 rearwardly to the position, as illustrated, wherein the element 45 is spaced from the frost 26 on the rear wall of the evaporator. The filler strip 47 adjacent the opening 46 assists in supporting the slideable member 36 and, in addition, the slideable member 36 may, if desired, be supported by the front support or bracket 37.

As in a form previously described, the slideable member 36 is resiliently biased forwardly toward a position wherein the element 45 is brought into engagement with the frost 26 on the rear wall of the evaporator. This bias is provided by a spring 49 mounted on the slideable member 36. One end 50 of the spring engages the rear support 38 and the other end 51 engages a spaced vertical section 52 of the wire or rod from which the slideable member 36 is formed. Each time the evaporator door 5 is moved to its open position the slideable member 36 is biased forwardly by the spring 49. When the evaporator door 5 is closed the bias of the spring 49 is overcome and the slideable member 36 is moved to the rearward position illustrated.

It can be seen that the amount of forward movement of the slideable member 36 upon the opening of the door is governed by the thickness of the layer of frost 26 on the rear wall of the evaporator. This is utilized by my invention for providing a visible indication of the amount of frost collected thereon. To provide such indication a wheel 53 is rotatably mounted on the front support or bracket 37. The wheel 53 is supported by a spacer 54 mounted on the screw 39, a washer 55 disposed between the head of the screw 39 and a section 56 of the spacer retaining the wheel 53 in its assembled position. The wheel 53 is mounted directly behind an opening 57 formed in the filler strip 47, a portion of the wheel 53 being clearly visible through the opening 57. In order to effect rotation of the wheel 53 so as to present different sections thereof to view through the opening 57 under different frost conditions, the indicating element 36 is provided with a depending pin 58 which extends through an opening or slot 59 in the rim 60 of the wheel 53. As the slideable member 36 moves forwardly when the evaporator door 5 is opened, the wheel 53 is rotated in a counter-clockwise direction as viewed in Fig. 6 by engagement of the pin 58 with the opening 59 in the wheel, the pin and slot connection allowing relative vertical movement of

the member 36 and the engaged portion of the rim of the wheel 53.

When the evaporator door 5 is closed the wheel 53 occupies the position illustrated in Figs. 6-9, and the slidable member 36 is disposed in a rearward position wherein the element 45 is spaced from the frost 26. When the evaporator door is opened the wheel is moved in a counterclockwise direction, as viewed in Fig. 6. The amount of rotation of the wheel and its ultimate position are determined by the amount of forward movement of the slidable member 36 and this forward movement, in turn, is determined by the thickness of the frost 26 on the rear wall 8 of the evaporator. Hence the final position of the wheel 53 indicates the thickness of frost. This indication may be effected by providing suitable legends or indicia on the rim 60 of the wheel 53 and upon the filler strip 47 adjacent the opening 57. For example, in Fig. 9 there is shown a specific form of indicia in which an arrow 61 is provided on the wheel and the filler strip 47 and the area beside the opening 57 is inscribed with the legend "Def." for "Defrost," and "Normal." If the arrow 61 occupies a position in the area covered by the legend "Normal" the frost layer on the evaporator is of a thickness below that at which defrosting is essential. Conversely, if the arrow occupies a position beside the legend "Def." this indicates that the thickness of the frost layer 26 is above a predetermined maximum and the evaporator should be defrosted promptly for efficient operation. Alternatively, as in the form previously described, a section of the rim 60 of the wheel 53 could be painted in some conspicuous color such as red so that the visibility of this red section or a substantial portion thereof through the opening 57 indicates the need for defrosting. Further adjacent sections or the entire remainder of the rim 60 may be painted in a contrasting color, such as green, so that, when substantially no frost is present on the rear wall 8 of the evaporator, an entirely green background is visible through the opening 57 and, as the frost layer 26 progressively builds up, an increasing red area is visible through the opening 57.

In Fig. 10 there is shown another modified form of my invention which is substantially the same as that illustrated in Figs. 6 through 9 inclusive except for small structural changes in the front support and in the front portion of the slidable member, and the specific manner of engagement between the slidable member and the wheel. The same numerals have been used to designate corresponding parts in Fig. 10 and in the previous figures. A slidable member 36' is positioned between the evaporator and the side wall of the liner 2 as in the forms previously described. A front support 62 is secured to the liner 2 and a wheel 53' is mounted on this support 62 and on the liner in the same manner as the wheel 53 in the form illustrated in Figs. 6 through 9 inclusive. The wheel 53' is disposed behind the opening 57 and the filler strip 47, so that a section of the rim of the wheel is visible through the opening 57. In order to effect rotation of the wheel 53' coincident with sliding movement of the member 36', a slot or opening 63 is provided in the side wall or face of the wheel 53' and a portion 64 of the slidable member 36' extends into the slot 63 for engagement with the wheel 53'. The slot 63 is elongated to provide for relative vertical movement between the engaged portion of the wheel 53' and the horizontally moving slidable member

36'. The movement of the wheel to indicate the thickness of the frost layer on the rear wall of the evaporator is the same as in the form illustrated in Figs. 6 through 9 and similar legends or coloring may be employed on the rim of the wheel end on the filler strip 47 to indicate the frost conditions. In order to provide for engagement of the slidable member 36' by the evaporator door 5 in its closed position the slidable member 36' includes a rod 65 which extends through an opening in the filler strip 47 and includes a portion 66 extending at right angles for providing a relatively flat area for contact with the door 5. The manner of operation of the form of invention illustrated in Fig. 10 is the same as that described in detail in connection with Figs. 6 through 9 inclusive.

While I have shown and described specific embodiments of my invention I do not desire my invention to be limited to the particular constructions shown and described and I intend, by the appended claims, to cover all modifications within the spirit and scope of my invention.

What I claim as new and desire to secure by Letters Patent of the United States is:

1. A refrigerator comprising a liner defining a food storage compartment, an evaporator upon which frost collects disposed in said compartment, a member slidably mounted adjacent said evaporator and including an element movable toward and away from said evaporator, the movement of said element toward said evaporator being intercepted by the frost collected on said evaporator whereby the amount of movement of said member is determined by the thickness of said frost, means for biasing said member for movement of said element toward said evaporator, an oscillatory indicating element having a directly visible portion, and means connecting said indicating element and said member for effecting oscillatory movement of said indicating element in accordance with said movement of said member whereby said visible portion of said indicating element indicates at least the general range of thickness of frost on said evaporator.

2. A refrigerator comprising a liner defining a food storage compartment, said liner including a side wall and a rear wall, an evaporator upon which frost collects disposed in said compartment, said evaporator including a side wall spaced from the side wall of said liner and a rear wall spaced from the rear wall of said liner, a member slidably mounted in the space between said side walls of said evaporator and said liner, said member including a laterally extending portion movable toward and away from said rear wall of said evaporator, the movement of said laterally extending portion toward said rear wall of said evaporator being intercepted by the frost collected on said rear wall of said evaporator whereby the amount of movement of said member is determined by the thickness of said frost, means for biasing said member forwardly for movement of said portion toward said evaporator, an oscillatory indicating element having a directly visible portion, means connecting said indicating element and said member for effecting oscillatory movement of said indicating element in accordance with said movement of said member whereby said visible portion of said indicating element indicates at least the general range of thickness of frost on said evaporator, and means for normally maintaining said laterally extending portion spaced from said frost against the bias of said biasing means.

3. A refrigerator including a liner defining a food storage compartment, an evaporator upon which frost collects disposed in said compartment, a member slidably mounted adjacent said evaporator and including an element movable toward and away from said evaporator, movement of said element toward said evaporator being intercepted by the frost collected on the evaporator whereby the amount of movement of said member is determined by the thickness of said frost, means for biasing said member for movement of said element toward said evaporator, an oscillatory indicating element having a directly visible portion, means connecting said indicating element and said member for effecting oscillatory movement of said indicating element in accordance with said movement of said member whereby said visible portion of said indicating element indicates at least the general range of thickness of frost on said evaporator, and a door for said evaporator, said door engaging said member for maintaining said first-named element spaced from said frost against the bias of said biasing means.

4. A refrigerator having a liner defining a food storage compartment, an evaporator upon which frost collects disposed in said compartment, a member slidably mounted adjacent said evaporator and including an element movable toward and away from said evaporator, the movement of said element toward said evaporator being intercepted by the frost collected on the evaporator whereby the amount of movement of said member is determined by the thickness of said frost, a spring for biasing said member for movement of said element toward said evaporator, an oscillatory indicating element having a directly visible portion, means connecting said indicating element and said member for effecting oscillatory movement of said indicating element in accordance with said movement of said member whereby said visible portion of said indicating element indicates at least the general range of thickness of frost on said evaporator, a door for said evaporator, said door in its closed position engaging said member for maintaining said first-named element spaced from said frost, and means for biasing said door to its closed position with a force sufficient to overcome the bias of said spring.

5. A refrigerator comprising a liner defining a food storage compartment, said liner including a side wall and a rear wall, an evaporator upon which frost collects disposed in said compartment, said evaporator including a side wall spaced from the side wall of said liner and a rear wall spaced from the rear wall of said liner, a first support secured to the front portion of said side wall of said liner, a second support secured to the rear portion of said side wall of said liner, a member slidably mounted on said supports and disposed in the space between said side walls of said evaporator and said liner, said member including a laterally extending portion movable toward and away from the rear wall of said evaporator, the movement of said laterally extending portion toward said rear wall of said evaporator being intercepted by the frost collected on the evaporator whereby the amount of movement of said member is determined by the thickness of said frost, means for biasing said member forwardly for movement of said laterally extending portion toward said rear wall of said evaporator, an oscillatory indicating element having a directly visible portion, means connecting said indicating element and said member for effecting oscillatory movement of said indicating element in accordance with said movement of said member.

of said indicating element in accordance with said movement of said member whereby said visible portion of said indicating element indicates at least the general range of thickness of frost on said evaporator, and means for normally maintaining said laterally extending portion spaced from said frost against the bias of said biasing means.

6. A refrigerator comprising a liner defining a food storage compartment, said liner including a side wall and a rear wall, an evaporator upon which frost collects disposed in said compartment, said evaporator extending substantially the full width of said compartment and including a side wall spaced from the side wall of said liner and a rear wall spaced from the rear wall of said liner, a member slidably mounted in the space between said side walls of said evaporator and said liner, said member including a laterally extending portion movable toward and away from said rear wall of said evaporator, the movement of said laterally extending portion toward said rear wall of said evaporator being intercepted by the frost on said evaporator whereby the movement of said member is determined by the thickness of said frost, means for biasing said member forwardly for movement of said laterally extending portion toward said rear wall of said evaporator, a filler strip between said side wall of said evaporator and said side wall of said liner, said filler strip having an opening therein, said member projecting through said opening, an oscillatory indicating element having a directly visible portion, means connecting said indicating element and said member for effecting oscillatory movement of said indicating element in accordance with said movement of said member whereby said visible portion of said indicating element indicates at least the general range of thickness of frost on said evaporator, and a door for said evaporator, said door in its closed position engaging said member for normally maintaining said laterally extending portion spaced from said frost against the bias of said biasing means.

7. A refrigerator comprising a liner defining a food storage compartment, said liner including a side wall and a rear wall, an evaporator upon which frost collects disposed in said compartment, said evaporator including a side wall spaced from the side wall of said liner and a rear wall spaced from the rear wall of said liner, a bracket secured to the front portion of said side wall of said liner, said bracket having an opening therein, a stud mounted on the rear portion of said side wall of said liner, a member movably mounted on said bracket and said stud and disposed in the space between said side walls of said evaporator and said liner, said member extending through said opening in said bracket and including an elongated slot for receiving said stud, said member including a laterally extending portion movable toward and away from said rear wall of said evaporator, the movement of said laterally extending portion toward said rear wall of said evaporator being intercepted by the frost collected on said evaporator whereby the amount of movement of said member is determined by the thickness of said frost, means for biasing said member forwardly for movement of said laterally extending portion toward said rear wall of said evaporator, an oscillatory indicating element having a directly visible portion, and means connecting said indicating element and said member for effecting oscillatory movement of said indicating element in accordance with said movement of said member.

ber whereby said visible portion of said indicating element indicates at least the general range of thickness of frost on said evaporator.

8. A refrigerator comprising a liner defining a food storage compartment, an evaporator upon which frost collects disposed in said compartment, a stationary support member, a second member movably mounted on said support member and including an element movable toward and away from said evaporator, the movement of said element toward said evaporator being intercepted by the frost collected on the evaporator whereby the amount of movement of said member is determined by the thickness of said frost, means for biasing said second member for movement of said element toward said evaporator, and means for normally maintaining said element spaced from said frost against the bias of said biasing means, one of said members including a slot inclined with respect to the line of movement of said second member, the other of said members including a pivoted oscillatory arm having a pin extending into said slot whereby said movement of said second member causes a pivoting of said arm and determines the position of said arm, said arm further including a directly visible portion for directly indicating the thickness of frost on said evaporator.

9. A refrigerator comprising a liner defining a food storage compartment, an evaporator upon which frost collects disposed in said compartment, a stationary support member, a second member movably mounted on said support member and including an element movable toward and away from said evaporator, the movement of said element toward said evaporator being intercepted by the frost collected on said evaporator whereby the amount of movement of said member is determined by the thickness of said frost, means for biasing said second member for movement of said element toward said evaporator, and means for normally maintaining said element spaced from said frost against the bias of said biasing means, said support member including a slot inclined with respect to the line of movement of said second member, said second member including a pivoted arm having a pin extending into said slot whereby said movement of said second member causes a pivoting of said arm and determines the position of said arm, said arm further including a directly visible portion for indicating at least the general range of thickness of frost on said evaporator.

10. A refrigerator comprising a liner defining a food storage compartment, an evaporator upon which frost collects disposed in said compartment, a stationary support member, a member movably mounted on said support member and including an element movable toward and away from said evaporator, the movement of said element toward said evaporator being intercepted by the frost collected on said evaporator whereby the amount of movement of said member is determined by the thickness of said frost, means for biasing said second member for movement of said element toward said evaporator, means for normally maintaining said element spaced from said frost against the bias of said biasing means, said second member including a front face having an opening therein, an oscillatory indicating element, and means connecting said indicating element and said second member for effecting oscillatory movement of said indicating element in accordance with said movement of said second member, said indicating element including a por-

tion movably disposed behind said face and adapted to have varying amounts exposed through said opening depending on the thickness of frost on said evaporator.

11. A refrigerator comprising a liner defining a food storage compartment, an evaporator upon which frost collects disposed in said compartment, a stationary support member, a second member movably mounted on said support member and including an element movable toward and away from said evaporator, the movement of said element toward said evaporator being intercepted by the frost collected on the evaporator whereby the amount of movement of said member is determined by the thickness of said frost, means for biasing said second member for movement of said element toward said evaporator, means for normally maintaining said element spaced from said frost against the bias of said biasing means, said second member including a front face having an opening therein, a pivoted arm, means connecting said pivoted arm and said second member for effecting rotational movement of said pivoted arm in accordance with said movement of said second member, said arm including a portion movably disposed behind said face and adapted to have varying amounts exposed through said opening depending on the thickness of frost on said evaporator.

12. A refrigerator comprising a liner defining a food storage compartment, an evaporator upon which frost collects disposed in said compartment, a stationary support member, a second member movably mounted on said support member and including an element movable toward and away from said evaporator, the movement of said element toward said evaporator being intercepted by the frost collected on said evaporator whereby the amount of movement of said second member is determined by the thickness of said frost, a door for said evaporator, said door in its closed position engaging said second member for maintaining said element spaced from said frost, a spring engaging said second member and said support member for biasing said second member for movement of said element toward said evaporator, said second member including a front face having an opening therein, a pivoted arm, means connecting said pivoted arm and said second member for effecting rotational movement of said arm in accordance with said movement of said second member, said arm including a portion movably disposed behind said face and adapted to have varying amounts exposed through said opening depending on the thickness of frost on said evaporator.

13. A refrigerator comprising a liner defining a food storage compartment, an evaporator upon which frost collects disposed in said compartment, a stationary support member, a second member movably mounted on said support member and including an element movable toward and away from said evaporator, the movement of said element toward said evaporator being intercepted by the frost collected on said evaporator whereby the amount of movement of said second member is determined by the thickness of said frost, means for biasing said second member for movement of said element toward said evaporator, and means for normally maintaining said element spaced from said frost against the bias of said biasing means, said second member including a front face having an opening therein, said support member including a slot inclined with respect to the line of movement of said second member, said

13

second member including a pivoted arm having a pin extending into said slot whereby said movement of said second member causes a pivoting of said arm, said arm including a portion disposed behind said front face and adapted to have varying amounts exposed through said opening depending on the thickness of frost on said evaporator.

14. A refrigerator comprising a liner defining a food storage compartment, an evaporator upon which frost collects disposed in said compartment, a stationary support member, a second member movably mounted on said support member and including an element movable toward and away from said evaporator, the movement of said element toward said evaporator being intercepted by the frost collected on said evaporator whereby the amount of movement of said member is determined by the thickness of said frost, means for biasing said second member for movement of said element toward said evaporator, and means for normally maintaining said element spaced from said frost against the bias of said biasing means, said second member including a front face having an opening therein, said second member including a second face spaced rearwardly from said front face and directly visible through said opening, said support member including a slot inclined with respect to the line of movement of said second member, said second member including a pivoted arm having a pin extending into said slot whereby said movement of said second member causes a pivoting of said arm, said arm including a portion disposed behind said front face and in front of said second face and adapted to have varying amounts exposed through said opening and to block to varying degrees visibility of said second face depending upon the thickness of frost collected on said evaporator, said second face being of one color and said portion of said pivoted arm being of a contrasting color.

15. A refrigerator comprising a liner defining a food storage compartment, an evaporator upon which frost collects disposed in said compartment, a member movably mounted adjacent said evaporator and including an element movable toward and away from said evaporator, the movement of said element toward said evaporator being intercepted by the frost collected on said evaporator whereby the amount of movement of said member is determined by the thickness of said frost, means for biasing said member for movement of said element toward said evaporator, a wheel rotatably mounted at the forward portion of said compartment, means connecting said wheel and said member for effecting movement of said wheel in accordance with said movement of said member whereby the position of said wheel indicates at least the general range of thickness of frost on said evaporator, and means for normally maintaining said element spaced from said frost against the bias of said biasing means.

16. A refrigerator comprising a liner defining a food storage compartment, said liner including a side wall and a rear wall, an evaporator upon which frost collects disposed in said compartment, said evaporator extending substantially the full width of said storage compartment and including a side wall spaced from the side wall of said liner and a rear wall spaced from the rear wall of said liner, a member movably mounted adjacent said evaporator and including a laterally extending portion movable toward and away from said rear wall of said evaporator, the movement of said laterally extending portion toward

14

said evaporator being intercepted by the frost collected on said evaporator whereby the amount of movement of said member is determined by the thickness of said frost, means for biasing said member forwardly for movement of said laterally extending portion toward said evaporator, a filler strip between said side wall of said evaporator and said side wall of said liner, said filler strip having an opening therein, a wheel rotatably mounted on said liner behind said opening in said filler strip, a portion of said wheel being exposed through said opening, means connecting said wheel and said member for effecting rotational movement of said wheel in accordance with said movement of said member whereby the portion of said wheel exposed through said opening indicates at least the general range of thickness of frost collected on said evaporator, and means for normally maintaining said laterally extending portion of said member spaced from said frost against the bias of said biasing means.

17. A refrigerator comprising a liner defining a food storage compartment, an evaporator on which frost collects disposed in said compartment, a member movably mounted adjacent said evaporator including an element movable toward and away from said evaporator, the movement of said element toward said evaporator being intercepted by the frost collected on said evaporator whereby the amount of movement of said member is determined by the thickness of said frost, means for biasing said member for movement of said element toward said evaporator, a wheel rotatably mounted at the forward portion of said compartment, said wheel including a rim having an opening therein, said member including a pin extending into said opening for effecting rotational movement of said wheel in accordance with said movement of said member whereby the position of said wheel indicates at least the general range of thickness of frost collected on said evaporator, and means for normally maintaining said element spaced from said frost against the bias of said biasing means.

18. A refrigerator comprising a liner defining a food storage compartment, said liner including a side wall and a rear wall, an evaporator upon which frost collects disposed in said compartment, said evaporator including a side wall spaced from the side wall of said liner and a rear wall spaced from the rear wall of said liner, a first support secured to the front portion of said side wall of said liner, a second support secured to the rear portion of said side wall of said liner, a member movably mounted on said supports and disposed in the space between said side walls of said evaporator and said liner, said member including a laterally extending portion movable toward and away from said rear wall of said evaporator, the movement of said portion toward said rear wall of said evaporator being intercepted by the frost collected on said rear wall of said evaporator whereby the amount of movement of said member is determined by the thickness of said frost, a spring engaging said member and one of said supports for biasing said member forwardly for movement of said laterally extending portion toward said rear wall of said evaporator, a wheel mounted on said first support, said member including means for engaging said wheel for effecting rotational movement of said wheel in accordance with said movement of said member whereby the position of said wheel indicates at least the general range of thickness of the frost collected on the rear wall of said evapo-

rator, and means for normally maintaining said laterally extending portion spaced from said frost against the bias of said biasing means.

19. A refrigerator comprising a liner defining a food storage compartment, said liner including a side wall and a rear wall, an evaporator upon which frost collects disposed in said compartment, said evaporator extending substantially the full width of said storage compartment and including a side wall spaced from the side wall of said liner and a rear wall spaced from the rear wall of said liner, a member movably disposed in the space between said side walls of said evaporator and said liner, said member including a laterally extending portion movable toward and away from said rear wall of said evaporator, the movement of said laterally extending portion toward said rear wall of said evaporator being intercepted by the frost collected on said rear wall of said evaporator whereby the amount of movement of said member is determined by the thickness of said frost, means for biasing said member forwardly for movement of said laterally extending portion toward said rear wall of said evaporator, a filler strip between said side wall of said evaporator and said side wall of said liner, said filler strip having a first opening therein, said member including a second portion extending through said opening, a door for said evaporator, said door in its closed position engaging said second portion of said member for normally maintaining said laterally extending portion spaced from said frost against the bias of said biasing means, said filler strip having a second opening therein, and a wheel rotatably mounted behind said filler strip and having a portion exposed to view through said opening, said member including means for engaging said wheel to rotate said wheel in accordance with

said movement of said member whereby the amount of rotation of said wheel is determined by the thickness of frost collected on said rear wall of said evaporator, said wheel and said filler strip adjacent said opening including indicia for indicating at least the general range of thickness of frost on the rear wall of said evaporator.

20. A refrigerator comprising a liner defining a food storage compartment, an evaporator on which frost collects disposed in said compartment, a member movably mounted adjacent said evaporator and including an element movable toward and away from said evaporator, the movement of said element toward said evaporator being intercepted by the frost collected on said evaporator whereby the amount of movement of said member is determined by the thickness of said frost, means for biasing said member for movement of said element toward said evaporator, a wheel rotatably mounted at the forward portion of said compartment, said wheel having an elongated opening in the side thereof, said member including a pin extending into said elongated opening for rotating said wheel in accordance with said movement of said member whereby the position of said wheel indicates at least the general range of thickness of frost collected on said evaporator, and means for normally maintaining said element spaced from said frost against the bias of said biasing means.

RICHARD J. CARBARY.
